(57) **CLAIM**

The ornamental design for combined barbecue shelves and console, as shown and described.

DESCRIPTION

FIG. 1 is an isometric view of a combined barbecue shelves and console showing a first variant the new design;

FIG. 2 is a front view of the combined barbecue shelves and console of FIG. 1;

FIG. 3 is a top view of the combined barbecue shelves and console of FIG. 1;

FIG. 4 is an end view of the combined barbecue shelves and console of FIG. 1;

FIG. 5 is an isometric view of the combined barbecue shelves and console showing a second variant the new design;

FIG. 6 is a front view of the combined barbecue shelves and console of FIG. 5;

FIG. 7 is a top view of the combined barbecue shelves and console of FIG. 5;

FIG. 8 is an end view of the combined barbecue shelves and console of FIG. 5;

FIG. 9 is an isometric view of a combined barbecue shelves and console showing a third variant the new design;

FIG. 10 is a front view of the combined barbecue shelves and console of FIG. 9;

FIG. 11 is a top view of the combined barbecue shelves and console of FIG. 9; and,

FIG. 12 is an end view of the combined barbecue shelves and console of FIG. 9.

The design is shown in solid lines in the drawings. The details shown in broken lines are for illustrative purposes only and form no part of the claimed design.
